UNITED STATES PATENT OFFICE.

HERMAN C. PRIEBE, OF BLUE ISLAND, ILLINOIS.

DRAFT-GEAR.

1,302,704.

Specification of Letters Patent.

Patented May 6, 1919.

Application filed October 16, 1916. Serial No. 125,766.

To all whom it may concern:

Be it known that I, HERMAN C. PRIEBE, a citizen of the United States, residing at Blue Island, in the county of Cook and State of Illinois, have invented a certain new and useful Improvement in Draft-Gears, of which the following is a full, clear, concise, and exact description, reference being had to the accompanying drawings, forming a part of this specification.

My invention relates to draft gears employed for coupling railway vehicles and which includes mechanism for absorbing or reducing buffing and pulling shocks. One feature of my present invention relates to the shock absorbing means and resides in an improved mounting therefor whereby the shock absorbing means may be assembled with and supported by the center sill or draft sill structure or other part of the car body independently of the coupling mechanism so that this assembly may be maintained in the event of removal of the coupling mechanism, which is some times accidental. Another feature of my invention resides in the provision of a swinging or oscillating mounting for the shock absorbing means whereby it may accompany the coupling mechanism in the movements of the latter and be ready in all positions of the coupling mechanism to function.

Another feature of my invention resides in an improved assembly of the center sill structure of a car body, the buffing plate or block or abutment, and the coupler yoke of a draft gear.

I will explain my invention more fully by reference to the accompanying drawing showing the preferred embodiment thereof and in which Figure 1 is a sectional plan view taken generally on line 1—1 of Fig. 2; Fig. 2 is a sectional elevation taken generally on line 2—2 of Fig. 1; and Fig. 3 is a sectional view taken generally on line 3—3 of Fig. 2.

Like parts are indicated by similar characters of reference throughout the different figures.

The coupler 1 includes a shank 2, which is connected with a yoke structure in a manner later to be set forth, the sides of the yoke structure shown being in the form of straps 3 through which openings 4 and 5 are provided for the reception of keys 6 and 7, the former of which constitutes a form of follower, the openings permitting the keys to

move inwardly with respect to the yoke when the coupler is subject to a sufficient pushing strain. The keys also project through openings 8 and 9 in the cheek plates 10 and 11 which are secured to the center sills 12 and 13, the openings 9 registering with the openings 5 and corresponding openings in the center sills when the gear is not under stress, the openings 8 similarly registering with the openings 4 and similar openings in the center sills.

Cotter pins 14 may be employed to prevent the withdrawal of the keys from the slots in the center sills that receive them. The yoke straps or sides 3 are disposed side by side so as to lie in the same general horizontal plane, in the construction shown in the drawing, but irrespective of the disposition of these yoke sides the inner end of the yoke is slotted to form an inwardly projecting fork 3¹ open at its inner end, the buffing block or abutment 15 (acting also as a support for the inner end of the coupler yoke) being received between the sides of the fork 3¹, this assembly permitting outward withdrawing movement of the coupler yoke without requiring the removal of the buffing block or abutment 15. The fork structure 3¹ enables me to place either side of the yoke structure on top. The buffing block or abutment is of heavy construction and is preferably arranged to float slightly about in pockets 16 formed in the cheek plates and closed at their outer ends by the center sills 12 and 13, though I do not wish to be limited to the total location of the buffing blocks between the center sills nor to the fact that they may move about between the center sills. As shown, the center sill 12 includes a section 12¹ that is riveted to the balance of the center sill, the section 12¹ closing the outer end of one of the pockets 16 after the abutment 15 has been passed endwise through this pocket into the other pocket. I prefer to permit the abutment 15 to move about between the center sills since the cheek plates may be located upon the center sills independently of each other and without regard to the alinement of the rivet holes in each center sill with the rivet holes in the other center sill, the abutment 15 shifting about to accommodate itself to the relative positions of the cheek plates.

The buffing mechanism illustrated is one which is in the form of spring mechanism, the form of buffer shown including two

springs 17 and 18, each formed of a plurality of spring plates or leaves, which are spaced apart by spacers 19 and which are maintained in assembly by bolts 20. As 5 illustrated the means for suspending the buffing mechanism from the car body resides in a sleeve 21 extending transversely between the sills at the upper portions thereof, this sleeve being held in place by means of 10 a bolt key 22. When the supporting device 21 is located at the upper part of the center sill structure the upper distance piece 19 rests thereupon and the buffing mechanism depends from the support. This buffing 15 mechanism is disposed in an upright position and passes between the inner end of the coupler yoke and the follower 6.

The yoke structure and the spring buffing mechanism illustrated are assembled when 20 the follower key 6 is not present in the structure, the coupled buffing springs 17, 18 being passed from beneath upwardly until the upper distance piece 19 is above the location of the support 21, this support being 25 passed between the springs 17 and 18 and below the upper distance piece 19 after the buffer springs have been located as described. After the buffer springs have been thus suspended upon the support 21 the 30 tapered end of the follower key 6 is inserted between the outer buffer spring 17 and the base of the slot at the inner end of the coupler shank 2 whereafter the follower key 6 is driven into place by means of a sledge 35 hammer so that the pair of springs 17, 18 will be under tension, pressing with heavy spring pressure respectively upon the fol-

lower key 6 and the inner end of the coupler yoke.

While I have herein shown and particularly described the preferred embodiment of my invention I do not wish to be limited to the precise details of construction shown as changes may readily be made without departing from the spirit of my invention, but 40 having thus described my invention I claim as new and desire to secure by Letters Patent 45 the following:—

1. A draft gear including a coupler having a coupler yoke, and a floating support 50 for the inner end of the coupler yoke from which the yoke is disengageable by outward movement thereof.

2. A draft gear including a coupler having a coupler yoke provided with an inwardly projecting fork upon its inner end, and a floating support for the inner end of the coupler yoke engaged between the arms of said fork.

3. A draft gear including a coupler having a coupler yoke, an abutment for engaging the inner end of the coupler yoke and from which the yoke is disengageable by outward movement thereof, and supporting 60 pockets for the abutment in which the end 65 portions of the abutment are free to shift.

In witness whereof, I hereunto subscribe my name this tenth day of October A. D., 1916.

HERMAN C. PRIEBE.
